Attorney.

UNITED STATES PATENT OFFICE.

FLOYD OGDEN, OF FISHERVILLE, KENTUCKY.

WATER-GATE.

SPECIFICATION forming part of Letters Patent No. 293,503, dated February 12, 1884.

Application filed April 6, 1883. (No model.)

To all whom it may concern:

Be it known that I, FLOYD OGDEN, a citizen of the United States, residing at Fisherville, in the county of Jefferson and State of Kentucky, have invented certain new and useful Improvements in Water-Gates, of which the following is a specification, reference being had therein to the accompanying drawings.

The object of my invention is to obtain a water-gate of the lightest practicable weight combined with delicately sensitive action, and a construction adapted to furnish better security against non-action caused by the accumulation of drift-wood under and upon the gate, and for the better security of inclosures against the passage of stock in or out. In the ordinary water-gates the frame-work is pendent from a beam crossing the stream, and the weight of the structure presses constantly downward, and thus causes the gate to catch the drift-wood and arrest its further motion, thus disabling the action of the gate, forcing it to and retaining it in an abnormal position, whereby stock generally, and especially hogs and the smaller animals, are allowed to get in and out of the inclosure.

Water-gates have heretofore been made with uprights erect upon a pivotal sill; and no claim is made to that feature of construction. The results desired are attained by the mechanism illustrated in the accompanying drawings, in which—

Figure 1 is a perspective view of my improvement. Fig. 2 is a perspective view of a modification thereof.

The gate is formed by a series of palings, referred to by the letter F, which are attached to a transverse beam or sill, (lettered C.) This sill is provided with bent arms D, having at their ends pintles or journals marked E, by means of which the gate is hung through

dead-eyes in angled standards marked A, for the double purpose of supporting the weight of the gate and bracing its position against the force of the current and moving drift-wood. 45 The standards A are to be made, preferably, of metal. By means of the position of the journaled arms D, the gate is so hung upon the standards A that its gravity will automatically force it back to a vertical position as soon as the pressure from the flowing water has ceased. By means of a chain, G, attached to stake H, the gate is secured against being disconnected from its bearings and washed away by a flood. 50

In the modification of the invention illustrated in Fig. 2 the sill is bowed, and is provided with journals at the ends, by which the gate is to be hung in angled standards A, which may be fixed either in the bed of the stream or attached to piers at the sides of the stream. 55

In the construction illustrated in Fig. 1 the angled standards are to be fixed in the bed of the stream.

The sills and palings may be of any desired shape or material that may prove to be most suitable for the purpose.

Having thus explained the construction and operation of my improvement, what I claim as new, and desire to secure by Letters Patent, is—

A flood-gate consisting of the sill C, the uprights F, the angular standards A, and the journals B, having bearings therein, substantially as and for the purpose specified. 75

In testimony whereof I affix my signature in presence of two witnesses.

FLOYD OGDEN.
